UNITED STATES PATENT OFFICE.

HIRAM PERCY MAXIM, HARRY M. POPE, AND HERBERT W. ALDEN, OF HARTFORD, CONNECTICUT, ASSIGNEES, BY MESNE ASSIGNMENTS, TO THE COLUMBIA AND ELECTRIC VEHICLE COMPANY, OF JERSEY CITY, NEW JERSEY.

VALVE-GEAR FOR EXPLOSIVE-MOTORS.

SPECIFICATION forming part of Letters Patent No. 645,177, dated March 13, 1900.

Application filed July 28, 1898. Serial No. 686,913. (No model.)

To all whom it may concern:

Be it known that we, HIRAM PERCY MAXIM, HARRY M. POPE, and HERBERT W. ALDEN, citizens of the United States, residing in the 5 city and county of Hartford, State of Connecticut, have invented certain new and useful Improvements in Motors, of which the following is a specification, reference being had to the accompanying drawings, forming a part 10 hereof.

This invention relates to motors in which power is applied to a reciprocating piston, and more especially to motors of this general class which are intended for use where it is 15 an object to prevent the access of dust, &c., to the working parts of the motor.

The object of this invention is to provide for the complete inclosing of the working parts of the motor, while at the same time 20 permitting free access to such working parts to be had when necessary.

The invention is illustrated in the accompanying drawings as applied to an explosive-engine of an ordinary type; but it is also applicable to other forms of motors, as will be 25 readily understood.

The nature of the invention will be more fully described hereinafter with reference to the drawings, in which—

30 Figure 1 is a vertical section in the plane of the axis of the crank-shaft (but with said shaft in elevation) of an explosive-engine to which the present improvements are applied. Fig. 2 is a vertical section on the plane indicated by the broken line 2 2 of Fig. 1 looking toward the right.

The cylinder E, with its wall or casing, piston E', connecting-rod E², valve-chest E³, and inlet and exhaust valves E⁴ E⁵, may be of any 40 ordinary or desired construction, form, and arrangement, the present invention not being directly concerned therewith. The cylinder is represented as having a flange E⁶, by which, with suitable bolts and nuts E⁷, it may be securely and closely united to the casing F, which is provided with a seat f to receive it; but any other suitable means of uniting the casing F and the casing or wall of the cylin-

der E may be employed. To facilitate manufacture, the casing F is formed in two parts, 50 which may be united into one by means of suitable flanges and bolts, as at F', substantially in the plane of the axis of the cylinder E. The casing F is so shaped as to receive the working parts of the engine, being provided with bearings, as F² and F³, for the crank-shaft G. The latter is formed in two parts, as is usual in motors of the class of that shown in the drawings, each part of the shaft being formed with crank-disks G' G², 60 the piston-rod or connecting-rod playing between the two crank-disks. A gear G⁶ on the end of the crank-shaft meshes with a gear H on a counter-shaft H'. The latter is supported in a suitable bearing carried by a bracket H², 65 which depends from a movable plate H³. The casing F is provided with an opening between the crank-shaft and the valve-chest large enough to admit the counter-shaft H', with its gear, and is closed by the plate H³, which may 70 be secured to its seat by suitable bolts H⁴. The shaft H' carries the cams H⁵, which co-operate in the usual manner with the valve-rods H⁶ H⁷, the latter passing through suitable guides H⁸ on the plate H³. In this manner the valve-gear can be removed readily, whenever required, without disturbing other parts of the motor, and yet it is at all times, when in use, completely inclosed within the continuous casing F. 75

The motor illustrated in the drawings, which is entirely self-contained, the bearings for the crank-shaft, as well as the valves, valve-gear, and cylinder, being wholly supported by the casing F, may be conveniently secured 80 by brackets F¹⁰ to any suitable support, such as a frame member of the machine with which it is used, suitable caps being provided, as indicated.

It will be understood that the casing above 90 referred to completely incloses and protects all of the working parts of the motor, being, in effect, continuous with the casing or wall of the cylinder, and that in the form shown it also supports the motor.

We claim as our invention—

In a motor, the combination with a crank-shaft, cylinder, valve-box and valve-rods, of a casing inclosing the crank-shaft and having an opening, a plate removably secured to 5 the casing to cover said opening and forming a continuation of the casing, said plate having guide-openings for the passage of the valve-rods, a counter-shaft mounted in a bearing carried by said plate and having a gear o meshing with a gear on the crank-shaft, and

valve-gear carried by said shaft, substantially as shown and described.

This specification signed and witnessed this 28th day of June, A. D. 1898.

HIRAM PERCY MAXIM.
HARRY M. POPE.
H. W. ALDEN.

In presence of—

H. E. HART,
W. B. GREELEY.
